UNITED STATES PATENT OFFICE.

WILLIAM J. HERREBOLD, OF KALAMAZOO, MICHIGAN.

PORATBLE HOIST.

1,393,218.

Specification of Letters Patent. Patented Oct. 11, 1921.

Application filed June 19, 1920. Serial No. 390,121.

To all whom it may concern:

Be it known that I, WILLIAM J. HERREBOLD, a citizen of the United States, residing at Kalamazoo, county of Kalamazoo, State of Michigan, have invented certain new and useful Improvements in Portable Hoists, of which the following is a specification.

This invention relates to improvements in portable hoists.

10 The main objects of this invention are to provide an improved portable hoist or hoisting truck for handling heavy objects and also objects of considerable size, in factories and in mills such as paper mills. A 15 further object is to provide a portable hoist which is very convenient to use and at the same time quite simple in structure.

Further objects, and objects relating to structural details will definitely appear from 20 the detailed description to follow.

I accomplish the objects of my invention by the devices and means described in the following specification. The invention is clearly defined and pointed out in the claims.

25 A structure which is a preferred embodiment of my invention is clearly illustrated in the accompanying drawing forming a part of this specification, in which:

Figure I is a side elevation of my improved portable hoist, a portion of one of 30 the standards being broken away to show structural details.

Fig. II is a front elevation of the structure shown in Fig. I.

35 Fig. III is a detail view partially in horizontal section on a line corresponding to line 3-3 of Figs. I and IV, showing details of the lifting screw driving means.

Fig. IV is a detail view partially in vertical section on a line corresponding to line 40 4-4 of Figs. I and III.

Fig. V is a detail view partially in vertical section on a line corresponding to line 45 5-5 of Fig. II, showing details of the support for the lifting screws.

In the drawing similar reference characters refer to similar parts throughout the several views, and the sectional views are taken looking in the direction of the little 50 arrows at the ends of the section lines.

Referring to the drawing, I provide four tubular standards 1 which are connected in pairs by the side braces 2, the braces in the structure illustrated being diagonally disposed. The rear carrying wheels 3 are mounted on the rear axle 4 which is se-

cured to the lower ends of the rear pair of standards. The front carrying wheels 5 are mounted on the axle 6, pivoted or supported by the king bolt 7 carried by the cross piece 60 8 at the lower ends of the front pair of standards.

The lifting screws 9 are disposed in the standards and are provided with cross heads 10 at their upper ends. The lifting screws 65 are slidably supported by bearing blocks 11 and 12, the bearing blocks 12 being arranged at the upper ends of the standards and the bearing blocks 11 being arranged at a considerable distance therefrom so that the 70 screws are supported for vertical movement. These bearing blocks are preferably of wood so as not to injure the screws. The lifting nuts 13 are supported by the lower blocks 11.

The driving rods or shafts 14 are mounted in ears 15 on the outer sides of the standards. On these shafts are driving worms 16 projecting through openings 17 to mesh with the nuts 13. The shafts 14 are 80 provided with hand wheels 18 at their front ends so that the screws may be raised and lowered as desired.

The track 19 is mounted centrally of the cross heads 10 so that the tackle carriage 85 20 may move back and forth thereon. A tackle 21 is shown conventionally in Fig. I.

My improved portable hoist or hoisting truck is especially adapted for use in handling heavy objects and objects of considerable size in factories and mills such as paper mills, for instance, the rolls of a paper making machine. In such use the truck may be backed up and the parts adjusted so that the track will be in alinement with 90 the I-beam above the paper making machine and the carriage run from the track onto the I-beam and vice versa in removing or replacing the roll. I have not attempted in the accompanying drawing to show the 100 relative proportion of parts, the drawings being illustrative only.

Having thus described my invention, what I claim as new and desire to secure by Letters Patent is:

1. In a structure of the class described, the combination of tubular standards, side braces connecting said standards in pairs, carrying wheels, axles therefor mounted on the lower ends of said standards, lifting 110 screws disposed within said standards, bearing blocks arranged within said stand-

ards to slidably support said screws, worm driving nuts supported within said standards by said bearing blocks, driving shafts mounted on the outer sides of the standards, 5 driving worms mounted on said shafts and projecting through openings therein to coact with said nuts, cross heads mounted on said screws, a track mounted centrally on said cross heads, and a tackle carriage on 10 said track.

2. In a structure of the class described, the combination of tubular standards, side braces connecting said standards in pairs, carrying wheels, axles therefor mounted on 15 the lower ends of said standards, lifting screws disposed within said standards, worm driving nuts supported within said standards, driving shafts mounted on the outer sides of the standards, driving worms 20 mounted on said shafts and projecting through openings therein to coact with said

nuts, cross heads mounted on said screws, a track mounted centrally on said cross heads, and a tackle carriage on said track.

3. In a structure of the class described, 25 the combination of a frame comprising tubular standards, carrying wheels, lifting screws disposed within said standards, worm driving nuts supported within said standards, driving shafts mounted on said 30 standards, driving worms mounted on said shafts to coact with said nuts, cross heads mounted on said screws, a track mounted on said cross heads, and a tackle carriage on said track. 35

In witness whereof I have hereunto set my hand and seal in the presence of two witnesses.

WILLIAM J. HERRBOLD. [L. s.]
